UNITED STATES PATENT OFFICE

95,451

DESIGN FOR A COMBINED WASHING MACHINE AND WRINGER THEREFOR

Raymond E. Patten, Bridgeport, Conn., assignor to General Electric Company, a corporation of New York

Application November 23, 1934, Serial No. 54,132

Term of patent 14 years

To all whom it may concern:

Be it known that I, Raymond E. Patten, a citizen of the United States, residing at Bridgeport, in the county of Fairfield, State of Connecticut, have invented a new, original, and ornamental Design for a Combined Washing Machine and Wringer Therefor, of which the following is a specification, reference being had to the accompanying drawing, forming a part thereof.

The figure is a perspective view of a combined

washing machine and wringer therefor showing my new design.

I claim:

The ornamental design for a combined washing machine and wringer therefor, substantially as shown.

In witness whereof, I have hereunto set my hand this 20th day of November, 1934.

RAYMOND E. PATTEN.
